(57) **CLAIM**

The ornamental design for portions of light-emitting device, as shown and described.

DESCRIPTION

FIG. 1 is a front perspective view of portions of light-emitting device showing our new design in accordance with a first embodiment;

FIG. 2 is another front perspective view of the portions of light-emitting device in accordance with the first embodiment;

FIG. 3 is a top plan view of the portions of light-emitting device in accordance with the first embodiment;

FIG. 4 is a bottom plan view of the portions of light-emitting device in accordance with the first embodiment;

FIG. 5 is a left side view of the portions of light-emitting device in accordance with the first embodiment;

FIG. 6 is a right side view of the portions of light-emitting device in accordance with the first embodiment;

FIG. 7 is a rear elevational view of the portions of light-emitting device in accordance with the first embodiment;

FIG. 8 is a front elevational view of the portions of light-emitting device in accordance with the first embodiment. The broken lines shown in all of the views are for illustrative purposes only and form no part of the claimed design;

FIG. 9 is a front perspective view of portions of light-emitting device showing our new design in accordance with a second embodiment;

FIG. 10 is another front perspective view of the portions of light-emitting device in accordance with the second embodiment;

FIG. 11 is a top plan view of the portions of light-emitting device in accordance with the second embodiment;

FIG. 12 is a bottom plan view of the portions of light-emitting device in accordance with the second embodiment;

FIG. 13 is a left side view of the portions of light-emitting device in accordance with the second embodiment;

FIG. 14 is a right side view of the portions of light-emitting device in accordance with the second embodiment;

FIG. 15 is a rear elevational view of the portions of light-emitting device in accordance with the second embodiment; and,

(Continued)

FIG. 16 is a front elevational view of the portions of light-emitting device in accordance with the second embodiment. The broken lines shown in all of the views are for illustrative purposes only and form no part of the claimed design.
